W RESON Design
STOVE DESIGN

Patented Jan. 3, 1856.

Act 199.

Pat. 799

William Resor, of Cincinnati, Ohio.
Letters Patent No. 799, Dated June 3, 1856.

The schedule referred to in these Letters Patent, and making part of the same.

To all whom it may concern:

Be it known that I, William Resor, of Cincinnati, Hamilton County, Ohio, have invented a new Design for a Cooking Stove called the "Lotus," and I do hereby declare that the following is a full and exact description thereof, reference being had to the annexed drawings making part of this specification.

In the accompanying drawing

Fig 1, is a perspective view.

Fig 2, represents the end fire door.

Fig 3, is an oven door

Fig 4, is a front fire door—these several doors are decorated at their central spaces with flowers and foliage (a).

The upper portion of the leg bears a shield (c) with a scolloped central boss (d). The lower end of the leg is enriched with a leaf (e).

I claim the design for the "Lotus" cooking stove substantially as described and represented.

In testimony whereof, I hereunto set my hand before two subscribing witnesses.
